UNITED STATES PATENT OFFICE

ERICH F. W. RICHTER, OF BERLIN, GERMANY, ASSIGNOR TO THE TABULATING MACHINE COMPANY, OF ENDICOTT, NEW YORK, A CORPORATION OF NEW JERSEY

AUTOMATIC CARD EJECTOR

Application filed February 8, 1927, Serial No. 166,626, and in Germany October 16, 1926.

This invention relates to record handling machines and more particularly to a device for automatically ejecting records from the machine after they have been operated upon by it. The invention is particularly adapted to card punching machines from which the cards are ordinarily manually removed from the machine after the punching operation.

According to my invention the operation of manually removing the cards from the machine is eliminated and automatic means are provided for ejecting the cards into a receptacle immediately after the completion of an operation upon them.

15 The principal object of the invention is to provide improved and simplified means for removing cards from a card handling machine.

20 A more specific object is to provide for automatically ejecting cards from the machine.

25 A further object of the invention is to provide an automatic card ejector for a card handling machine which is operated by the machine immediately upon completion of an operation upon a card.

30 A further object of the invention is to provide an automatic card ejector for a card handling machine in which cards are carried on a card carriage and in which the card carriage trips the ejector at the completion of its card carrying movement.

35 A further object of the invention is to provide an automatic card ejector for a card handling machine which will be automatically set for an ejecting operation when a card is inserted into the operating portion of the machine.

40 A further object of the invention is to provide an automatic card ejector for a card handling machine in which cards are carried by a card carriage and in which the ejector will be automatically set for an ejecting operation when the carriage is moved into position to receive a card.

45 Other objects and advantages of my invention will be obvious from the following particular description embodying the invention and of the accompanying drawings in which:

Fig. 1 is a side elevational view of a duplicating key punch with the auto ejector;

Fig. 2 is a plan view associated therewith partly in section of the automatic ejecting device;

55 Figs. 3 and 4 are side elevational views of the ejecting unit in different positions taken on line 3-3 of Fig. 2; and

Fig. 5 is a side sectional view of the ejector unit driving means taken on line 5-5 of Fig. 2.

60 Fig. 6 is a side partly sectional view of the punching section of the machine;

Fig. 7 is a detail of the escapement means, and

65 Fig. 8 is a plan view of a part of the punching section.

70 For the purpose of clearly disclosing my invention it has been shown as applied to a duplicating punch of the type shown in the copending application of F. Lee and B. Phillips, Serial No. 34,516, filed June 3, 1925.

75 The operation of the punch is fully explained in that application and will be explained in the present case only in sufficient detail to define its relation to the ejector mechanism. Referring to Fig. 1 it will be understood that the cards 15 may be fed one at a time into the punching section 33 by moving the handle 2 to the left. This operation moves the card carriage 16 (Fig. 2) to the right and picks the bottom card from the stack and deposits it on the carriage in position to have its first column punched. If the control of the punches is manual, the operator depresses the desired key 40 which

80 through a bell lever 41 (Fig. 6) advances an interposer 42 against a spring 43 over the head of a punch 44 normally held by a spring 45 in its uppermost position. Through means not essential to an understanding of the present invention and fully described in the copending application hereinbefore mentioned, the interposer 42 upon advancing closes a circuit through punch magnet 46 which attracts armature 47 to rock lever 48 and moves link 49 downwardly. The upper end of the latter is pivoted to a bail or hammer 50 and rocks the latter counterclockwise (as viewed in Fig. 6) about its pivot 51.

against the resistance of a spring 52. When the hammer nose 53 rocks downward, it moves into the notch 54 at the forward end of interposers which have not been advanced and has no effect on these interposers. The interposer which has been advanced will however be engaged on the upper edge by the nose 53 and will be depressed thereby thus depressing the punch 44 and causing punching. During downward movement of the interposer the bottom edge thereof engages a bail 55 and rocks it counterclockwise. The bail 55 is fixed to a shaft 56 (see Figs. 6 and 8) which carries at one end an arm 57 and an oppositely extending arm 58 (see Figs. 7 and 8). Arm 57 has a pin 59 fixed thereto which is loosely positioned in a hole 60 in a feed pawl 61. Arm 58 has a pin 62 seated in a notch at the forward end of a holding pawl 63 (see Fig. 7). Normally the pawl 61 is in engagement with a tooth on the escapement rack 64 which is provided at the bottom with teeth 65 meshing with gear 66 carried by the usual spring drum initially tensioned when the carriage was moved to the right to receive a new card. When the interposer rocks bail 55 and shaft 56 during a punching operation, the pin 60 moves upwardly and the pin 62 downwardly. The pawl 61 is thereby lifted from the escapement rack and moved by a spring 67 to the left (as viewed in Fig. 7) until the nose of the pawl rests on and slightly past the top of the next tooth. While this occurs, the pawl 63 has been moved down by pin 62 until it engages the escapement rack. The rack is thereby held from moving during punching. After the hammer 50 has been rocked to effect the downward movement of the interposer and associated punch, the circuit through magnet 46 is broken and armature 47 is released thereby returning the parts to initial position. The interposer rises and permits bail 55 and shaft 56 to return to initial position. Pin 60 thereupon moves downwardly and pin 62 upwardly. The pawl 63 thereupon rises and pawl 61 is allowed to move down, the escapement rack being moved by pinion 66 until the trough of the next tooth is engaged by the nose of pawl 61. Thus, each time a punching operation is effected, the rack is permitted to escape one tooth. The rack is rigid with and part of the card carriage 16. Thus, after the first column is punched the carriage automatically moves one step to the left to bring the card into position to have its second column punched. As each column is punched the step by step feeding movement of the carriage is repeated until finally all the card columns are properly punched and the carriage stands in its extreme position to the left where the punched card may be removed and the handle 2 again operated to feed the next card from the bottom of the stack and

move the card carriage to the right into position to receive it.

It has hitherto been necessary to manually remove the card from the card carriage after the latter has advanced into its extreme left position subsequent to the punching in the last card column. The present invention provides an automatic ejector which functions to remove the card from the carriage and deposit it in a suitable receptacle when the carriage advances the card from the last punching position. The ejector will now be described.

The reverse movement of the carriage 16 is effected by a rod 32 (see Fig. 5). The feed mechanism through which the reverse movement of the carriage is effected does not enter particularly into the present invention and will not be described as its operation is clearly explained in the copending application above referred to. It will be understood, however, that whenever the handle 2 is moved to the left to feed a card and incidentally restore the carriage 16 to its starting position the rod 32 will be likewise moved to the left. Rod 32 is enclosed in a slotted tube 3 (see Figs. 1 and 5) and when handle 2 is moved to the left rod 32 is pushed against another rod 4 to which is affixed at its left end a rack 5 coacting with gears 6. Abutting the free end of rack 5 is a spring 7 to which is fixed at its other end a slug 8 slidably mounted in the tube 3. A set screw 6a coacting with slug 8 enables the proper adjustment of the tension on the spring 7. When spring 7 is compressed rack 5 cooperating with gears 6 revolves a shaft 9 upon which is mounted the ejector unit 10 (see Fig. 3). This clockwise movement of the shaft 9 rocks the ejector unit 10 to the position indicated in Fig. 3. A latch 12 pivoted at 13 and biased by a spring 14 tends to hold the ejector unit in the position shown in Fig. 3. The ejector unit comprises a block 17 mounted on the shaft 9 and having an integral lower jaw 18. Coacting with lower jaw 18 is an upper jaw 20 pivoted at 19 on the block 17. A spring 21 tends to hold the upper jaw 20 against its coacting jaw 18. A pin or stud 22 fastened to the base of the punch protrudes through a hole in the lower jaw 18 and is of sufficient length to come into contact with the upper jaw 20 thereby holding the jaws 18 and 20 apart sufficiently for a card to easily slip between them as long as the ejector unit is latched by the latch 12 as shown in Fig. 3. An arm 23 fixed to the latch member 12 carries an adjustable set screw 24 which lies in the path of a disc 25 mounted on the card carriage 16 (see Fig. 2). When the last card column is punched the card carriage 16 moves one step further to the left causing the disc 25 to strike against the set screw 24 causing the arm 23 and the at-

tached latch 12 to move against the action of spring 14 whereupon the ejector unit is released and the shaft 9 carrying the ejector unit is rotated through the agency of 5 spring 7 and gears 6 to the ejecting position shown in Fig. 4. The card 15 by its final movement to the left frees its right hand edge and as the jaw 20 clears the pin 22, the card is gripped between the jaws 18 and 20 and carried around with the ejector unit. Just before the unit reaches the position shown in Fig. 4 the pin 26 protruding through a hole in the jaw 20 encounters a member 27 and pries the jaws apart against the tension of spring 21 thereby releasing the card 10 allowing it to fall into the receptacle 28 (see Fig. 1).

While I have shown and described and pointed out the fundamental novel features 15 of the invention as applied to a single modification it will be understood that various omissions and substitutions and changes in the form and details of the devices illustrated and in its operation may be made by 20 those skilled in the art without departing from the spirit of the invention. I intend to be limited therefore only as indicated by 25 the scope of the following claims.

I claim:

1. In a machine for operating upon records, a record carriage movable in one direction to feed records through the machine and in a reverse direction to receive records for feeding, an ejecting gripping mechanism controlled by said carriage for automatically gripping and ejecting the records from the machine at the completion of a feeding operation and means controlled by said carriage in its reverse movement for setting said ejecting mechanism in readiness for a subsequent ejecting operation.

2. In a machine of the class described, a record carriage movable in one direction to forward the records through the machine and in a reversed direction to receive records for feeding, an ejecting gripping mechanism controlled by said carriage for automatically gripping and ejecting a record from the machine at the completion of a feeding 45 operation and the ejection being complete irrespective of the reverse movement of the carriage and means for setting said ejecting mechanism in readiness for ejecting the next record fed by said carriage.

3. A record ejector including record gripping means, means for yieldingly urging said gripping means to ejecting position and a latch for releasably holding said gripping means in record receiving position.

4. A record ejector including coacting jaws for receiving and gripping a record and means for yieldingly urging said jaws together, means for yieldingly urging said coacting jaws to ejecting position, a latch for 50 releasably holding said gripping jaws in rec-

ord receiving position and means for automatically prying said jaws apart when in either position.

5. A machine comprising means for carrying a sheet through the machine for an 70 operation, ejecting means, means for actuating the ejecting means in the direction of the carrying means to remove a sheet directly from the carrying means, and means controlled when the carrying means is moved to 75 receive the next sheet for actuating the ejecting means opposite to the first-named direction into position to remove said next sheet from the carrying means.

6. A machine comprising means for carrying a sheet through the machine, means for actuating the carrying means, ejecting means for ejecting the sheet from the carrying means, and means for operating the ejecting means including a gear element driven by 80 85 said actuating means.

7. The invention as set forth in claim 6, in which a spring is provided for returning the said gear element to initial position.

8. The invention as set forth in claim 6, 90 in which a spring is provided for returning the said gear element to initial position, and means releasable by the carrying means is provided to prevent operation of said spring 95 until the carrying means has completed carrying of the sheet through the operating means.

9. A machine comprising a carriage for feeding a sheet through the machine, a single 100 ejecting unit for holding only one sheet at a time, and means for operating said ejecting unit to grip and eject each sheet carried by the carrying means, operation of said ejector operating means being initiated by said carriage and thereafter inherently completed independently of the carriage.

10. A card handling mechanism adapted 110 for cooperation with a card carriage comprising a trigger mechanism, means controlled by the card carriage when the latter moves to card receiving position to cock the same, and means controlled by card carriage upon movement of the same to card discharge position to trip the trigger mechanism and effect an ejection of the card from the carriage.

11. A card eject mechanism adapted for 115 cooperating with a movable card carriage to eject cards therefrom, said ejecting mechanism comprising a device including grippers with provisions for setting the same under the control of the card carriage to card receiving position, means adjustably under control of the card carriage for effecting gripping of a received card and for ejecting the same from said carriage.

12. The invention set forth in claim 11 for which a pivotal support is provided for the gripping means being rotatable about a fixed axis whereby a tilting over movement of the grippers and the card carried thereby may be 120 125 130

effected in ejecting the cards from the machine.

13. A card eject mechanism for a card punching machine or the like having a card carriage for advancing the card therethrough said mechanism comprising in combination means brought into operation by the card carriage reaching a determined position for gripping a card, and means thereupon automatically operable for turning over the card and delivering it to a storage receptacle irrespective of the further movement of the carriage.

14. A card eject mechanism for a punching machine or the like having a card carriage, said mechanism comprising a device settable to card receiving position, actuating means therefor, latching means for restraining operation of the actuating means, and means operated by the card carriage for moving the latching means to release the actuating means for actuating the device to grip and eject a card from the machine.

15. In a machine of the character described, an ejecting device comprising in combination a gripper for the card or like sheet, resilient means for urging it in a direction to eject a card, a detent normally holding the gripper in card receiving position against the action of the resilient means, and means for moving the card into engagement with the gripper and for concurrently moving the detent out of detaining position thereby enabling the aforesaid resilient means to move the gripper in a direction to eject the card gripped thereby.

16. A machine comprising means for operating on a record sheet, means for carrying a sheet through the operating means for an operation, ejecting means for the sheet on the carrying means, actuating means for the ejecting means, and a device driven by the carrying means for driving said actuating means.

17. The invention as set forth in claim 16 wherein means controlled by the carriage delays operation of said device to drive the said actuating means until the operation on the card is completed.

18. A machine comprising a frame, card operating means, a carriage for moving a card through the operating means, a shaft carried by the frame with its axis in a fixed position relative to the frame, an ejecting device including a base portion rigidly carried by said shaft, and means controlled by the carriage for actuating said shaft to cause the ejecting means to eject a sheet from the carriage.

19. A machine comprising a frame, card operating means, a carriage for moving a card through the operating means, a shaft carried by the frame with its axis in a fixed position relative to the frame, an ejecting device completely and solely carried by the

said shaft, and means controlled by the card carriage for operating said ejecting means to eject a card from the carriage.

20. A machine comprising card operating means, a carriage for moving a card through the operating means, ejecting means, a spring for actuating said ejecting means to eject a card from the carriage, and means for energizing said spring when the carrying means is moved to receive a record sheet.

21. The invention as set forth in claim 20, wherein said means for energizing the spring is operated by the carrying means and effects return of the ejecting means to initial position in readiness to eject another sheet.

22. A machine comprising means for feeding record sheets through the machine, means for ejecting the sheets from the feeding means, and means energized by the feeding means during movement of the latter in one direction for subsequently actuating said ejecting means to eject a sheet after the last operation thereon.

23. A machine comprising means for carrying a sheet through the machine, ejecting means for the sheet including a pair of elements for seizing the sheet on the carrying means, and means controlled by the carrying means when the latter reaches a predetermined position for actuating said elements to grip and completely eject a sheet irrespective of further operation of said carrying means.

24. A machine comprising means for carrying a sheet through the machine for an operation, ejecting means for the sheet on said carrying means including elements having a predetermined position for receiving a sheet, means for setting said elements in said position while the carrying means is moving to receive a sheet, and means controlled by the carrying means when it moves a sheet into the bite of said elements for actuating said elements to seize the sheet between them and eject the sheet irrespective of the further operation of said carrying means.

25. The machine such as described in claim 24, the means for setting said elements in said receiving position being operated by said carrying means.

26. A machine comprising means having a forward movement for carrying a sheet through the machine, ejecting means for the sheet on said carrying means including elements having a predetermined position for receiving the sheet, means for setting said elements in said position before the carrying means completes its forward carrying movement, and means controlled by the carrying means when it completes the forward carrying movement for operating said elements to grip and eject a sheet irrespective of further movement of the carrying means.

27. A machine such as described in claim 26, the means for setting said elements in said

sheet-receiving position being operated by said carrying means.

28. A card handling mechanism including a card carriage, a trigger mechanism for ejecting the card from said carriage and automatically operable to flip and turn the card over to eject position, means controlled by the carriage when the latter moves to card receiving position to cock the trigger mechanism, and means controlled by the carriage upon movement of the latter to card discharge position to trip the trigger mechanism and effect operation thereof to eject a card.

29. A card eject mechanism comprising pivotally mounted grippers, means for holding said grippers open to receive a card until said card is completely entered into the grippers, spring means tending to rotate said grippers about their pivot to eject position, means for restraining operation of said spring means until the card is completely entered into the grippers, and means for releasing said restraining means when the card is completely entered into the grippers to cause operation of said spring means for rotating the grippers, to eject position, the latter upon rotation first gripping the card and then flipping it over to eject position.

30. In a card handling device, an ejecting device including a pair of elements for seizing and ejecting a card, a carriage for feeding the card towards the elements while the latter are stationary, and means controlled by the carriage for driving the elements to effect complete ejection thereby of a card on the carriage before the carriage receives the next card.

31. The device as described in claim 30, and means for moving said elements opposite to the direction of their ejecting movement into a position for receiving the next card on the carriage.

In testimony whereof I hereto affix my signature.

ERICH FRIEDRICH WILHELM RICHTER.
